INVENTOR,

Chas. A. Thompson.
BY
Wm. F. Bellamy

ATTORNEY,

UNITED STATES PATENT OFFICE.

CHARLES A. THOMPSON, OF NEW YORK, N. Y.

PROCESS OF MAKING DUPLICATE COPIES OF WRITINGS, &c.

SPECIFICATION forming part of Letters Patent No. 398,675, dated February 26, 1889.

Application filed June 18, 1887. Renewed February 4, 1889. Serial No. 298,552. (No model.)

To all whom it may concern:

Be it known that I, CHARLES A. THOMPSON, a citizen of the United States of America, and a resident of the city, county, and State of New York, have invented certain new and useful Improvements in the Process of Making Duplicate Copies of Writings, &c., and in apparatus therefor, of which the following is a specification.

10 This invention relates to the production of a transfer-sheet for manifold copying for producing autographic writing, printing, or similar delineation by impression; and my improvement consists in the method, hereinafter described, and particularly pointed out in the claims, by which my improved transfer-sheet is produced.

In the accompanying drawings, Figure 1 is a vertical sectional view of a press in which 20 the impressions from the transfer-sheets prepared by this method may be printed or transferred. Fig. 2 is a similar view illustrating a different disposition of the transfer-sheet. Fig. 3 is a sectional view of the transfer-sheet 25 between the sheets communicating the printing medium to the said sheet, showing the preferred method of imparting the printing medium in the delineations upon the sheet. Fig. 4 is a similar view showing a slightly-different 30 method of imparting the printing medium in the delineations upon the sheet, and Fig. 5 is a perspective view of a transfer-sheet secured upon a re-enforcing backing.

The same letters of reference indicate the 35 same or corresponding parts in all the figures.

In the drawings, the letter A represents the transfer-roller, upon which the transfer-sheet C, prepared as will hereinafter be described, is secured.

40 B indicates the impression-roller; D, the roll of copying-paper upon which the transfers are made; E, the guide-roller, which immerses the paper into the water-receptacle, and F F the squeezing-rollers, which remove the superfluous water from the copying-paper. All 45 these parts may be substituted by any other suitable printing or copying device, being merely illustrated for the purpose of showing how the transfer-sheet may be used and having no direct bearing upon or connection with 50 the invention.

In Fig. 2 is shown another manner of using the press, the transfer-sheet being in this case separate from the roller and being carried between the transfer-roller and the impression-roller, together with the copying-paper. The transfer-sheet is preferably prepared by placing it between two sheets, a a, as shown in Fig. 3, the said sheets being impregnated or coated with a composition of 6c divisible aniline carbon or similar pigment with the prepared sides or faces of such sheets placed against the transfer-sheet, which is of such a character that it will absorb and retain the composition of the sheets when receiving the same at all points where pressure is brought to bear against the sheets. When, now, writing or printing is effected upon the upper sheet by means of a pencil, stylus, type-writer, form of type, or other suitable 70 means of impression, the composition of the inclosing-sheets will be imparted to and absorbed by the transfer-sheet from both sides at all points subjected to the pressure of the delineations of such writing or printing, and the composition will, on account of the nature of the transfer-sheet, penetrate the same and remain in the same, so that the impression will stand in obverse or in positive form upon one side of the sheet and in reverse or in 80 negative form upon the other side and extend through the entire thickness of the sheet. When, now, the sheet is passed through the press shown in the drawings or through a similar press, the impregnated delineations 85 upon the transfer-sheet will be capable of being impressed upon and communicated to the copying-paper, the thoroughly-impregnated characters or configurations of the sheet extending through its entire thickness being capable of rendering a greater number of impressions than when only impregnated from one side of the sheet. The transfer-sheet may, however, be only impregnated from one side, as shown in Fig. 4, when the transfer-sheet is 90 placed face down upon the prepared sheet and has the writing made in obverse or positive form upon its back, receiving the delineations in reverse or negative form upon its face, the composition penetrating the points subjected 95 to the pressure of the delineating medium. 100

For the purpose of re-enforcing the sheet

and rendering it more durable, it may be secured to a backing, II, as shown in Fig. 5 of the drawings.

Having thus described my invention, I claim 5 and desire to secure by Letters Patent of the United States—

1. The improved method of preparing a transfer-sheet for manifold printing or copying, consisting in placing the absorbent sheet 10 face down upon a surface impregnated and coated with the copying or printing medium or material, and producing by pressure the desired delineations or characters in obverse upon the back of the transfer-sheet, causing 5 the said sheet to absorb the copying or printing medium at the points of impression and to have the delineations or characters to appear in reverse upon the face of the sheet absorbed into the same, as shown and described.
2. The improved method of preparing a transfer-sheet for manifold copying or printing, consisting in placing the absorbent trans-

fer-sheet between two sheets having their facing sides coated or impregnated with the printing or copying medium, and thereupon 25 producing the desired delineations or characters by pressure upon the back of one of the inclosing sheets, causing the transfer-sheet to absorb the copying or printing medium at the points of pressure and to be thoroughly impregnated therewith from both sides, 30 producing the impressed delineations or characters to appear in obverse upon the back of the transfer-sheet and in reverse upon the face of the same, and to be absorbed through the 35 entire thickness of the sheet from both sides, as shown and described.

In testimony that I claim the foregoing as my invention I have signed my name in presence of two witnesses.

CHARLES A. THOMPSON.
